EX

OR D 12,589

DESIGN FOR AN ORNAMENTAL WINDOW-SHADE.

Design No. 12,589, dated December 6, 1881.

UNITED STATES PATENT OFFICE.

PAUL RICHTER, OF NEW YORK, N. Y., ASSIGNOR TO WARREN FULLER & CO.,
OF SAME PLACE.

DESIGN FOR AN ORNAMENTAL WINDOW-SHADE.

SPECIFICATION forming part of Design No. 12,589, dated December 6, 1881.

Application filed November 1, 1881. Term of patent 3½ years.

To all whom it may concern:

Be it known that I, PAUL RICHTER, a citizen of the United States, residing at and doing business in the city of New York, in the county and State of New York, have invented and produced a new and original Design for Ornamenting Window Shades or Curtains, of which the following is a full and clear description, reference being had to the accompanying drawing.

The said drawing consists of an elevation of the portion of the curtain containing my improved ornamental device.

The design or ornamentation consists of the following: Two narrow lines, A A', about one-eighth or one-quarter of an inch wide, more or less, extend across the whole width of the curtain, at about five or six inches apart, and below the lower one of these lines or bands, A, is a broader band or base-piece, A², equal in length to the line A, and about five or six times the width of the said line or band A. The base or band A² is ornamented with a longitudinal running scroll or enrichment, a, with two parallel rows of dots, a' and a², by the sides of and parallel with it. The field of ornament between the lines A A' is enriched with a center shell-like figure, B, with two circular-bodied vase-shaped figures, C C', near the sides of the curtain, and oval shield-like figures D D', placed in the space between the ornaments B C and B C', respectively, while the remainder of the field of ornamentation is richly covered

with foliated vines and flowers F, some of which extend above the line A' and some below the line A. The shell piece or central figure, B, is somewhat in equilateral Gothic form of contour, and is filled in with an elaborate scroll-work, b, while above this central figure the foliated and floral crest B' rises some inches above the other parts of the design, so as to form a prominent and picturesque central apex high above the rest of the ornamentation of the design. The height of the vases C C' equals the width of the ornamental field between the lines A and A', and they show foliated plants and figures projecting out of the tops of them above the line A'. The various parts of this ornamentation and the ground on which it is printed may be of any desired colors, and the relative positions of the ornaments C C' and D D' may of course be transposed without affecting the design herein described.

Having described my invention or design, I claim—

The ornamental design for a window curtain or shade, consisting of the lines A, A', and A², the central figure, B, the vase ornamentation C C', the intermediate figures, D D', and the foliation F, designed and arranged substantially as described.

PAUL RICHTER.
